UNITED STATES PATENT OFFICE.

IRVIN D. FOX, OF AUSTIN, MINNESOTA.

DESIGN FOR A LIQUID-MEASURE MIXER.

53,069.

Specification for Design.

Patented Mar. 11, 1919.

Application filed December 10, 1917. Serial No. 206,551. Term of patent 14 years.

To all whom it may concern:

Be it known that I, IRVIN D. Fox, a citizen of the United States, residing at Austin, in the county of Mower, State of Minnesota, have invented a new, original, and ornamental Design for a Liquid-Measure Mixer, of which the following is a specification, reference being had to the accompanying drawing, forming part thereof.

The figure is a perspective view of a liquid measure-mixer, showing my new design.

I claim:

The ornamental design for a liquid measure-mixer, as shown.

IRVIN D. FOX.
